UNITED STATES PATENT OFFICE.

PATRICK J. RYAN, OF PHILADELPHIA, PENNSYLVANIA, ASSIGNOR OF ONE-HALF TO PATRICK A. DEMPSEY, OF SAME PLACE.

STOCKLESS ANCHOR.

SPECIFICATION forming part of Letters Patent No. 638,147, dated November 28, 1899.

Application filed February 3, 1899. Serial No. 704,388. (No model.)

To all whom it may concern:

Be it known that I, PATRICK J. RYAN, a citizen of the United States, residing in Philadelphia, Pennsylvania, have invented certain 5 Improvements in Stockless Anchors, of which the following is a specification.

My invention consists of certain improvements in that class of anchors known as "stockless" anchors, in which the flukes are 10 hung upon a central shank, so as to be free to swing to a certain extent to either side of the same, the object of my improvements being to so construct an anchor of this character that it will comprise but few and 15 simple parts, which, while securely retained in position when the anchor is in use, can be readily put together or taken apart when occasion requires, the free swing of the flukes in respect to the shank to their limit in either 20 direction being provided for and a firm hold of the flukes of the anchor upon the bottom being also insured.

In the accompanying drawings, Figure 1 is a perspective view of an anchor constructed 25 in accordance with my invention. Fig. 2 is a perspective view showing parts of the anchor detached from each other. Fig. 3 is a longitudinal section showing the anchor as it appears when in use. Fig. 4 is a transverse 30 section showing the flukes and part of the shank in elevation, and Fig. 5 is a view illustrating a modification of the invention.

11 represent the two flukes of the anchor, which are connected by and preferably 35 formed integral with a bridge-piece 2, in which is a central longitudinal opening 3, terminating at the forward side of the bridge-piece in a curved slot 4, the latter being flanked on the inner side by curved ribs 5, owing to the 40 fact that the slot 4 is of less lateral dimensions than the opening 3. Into the opening 3 of the bridge-piece is inserted from the rear a block 6, which has in its forward face a curved recess or socket 7 and is retained 45 in position by means of a transverse bolt 8, passing through an opening in the block and through openings 9, projecting rearwardly from the bridge-piece 2, this bolt being secured in position by riveting or by means 50 of a pin or nut, as desired, so that it can be

removed when it is desired to separate the parts of which the anchor is composed. The socket 7 of the block 6 constitutes a bearing for the inner end of a head 10, formed upon the shank 11 of the anchor, said head being 55 somewhat wider than the shank, so as to form ribs 12 for bearing against the shoulders 5 of the bridge-piece. While, therefore, free swinging movement of the fluke and shanks in respect to each other is permitted 60 within the limits of the slot 4, the fluke structure and the shank are firmly retained in position in respect to each other longitudinally by reason of the bearing of the head of the shank against the block 6 and shoulders 5. 65

The block 6 is recessed at top and bottom, so that when it is inserted in the opening 3 of the bridge-piece 2 openings 13 are formed above and below the block, through which openings the water can freely pass, thereby 70 preventing any such accumulations of sand or mud in the chamber 3 as would tend to interfere with the swinging of the shank and flukes in respect to each other to the full limit permitted by the slot 4. 75

As the bearing of the shank 11 upon the bridge-piece 2 of the fluke structure of the anchor is very close to the pivotal bearing of the head 10 of the shank upon the block 6, the upward or lifting strain of the shank upon the anchor is very slight as compared with its forward strain or pull. Hence the flukes will take a firm hold upon the bottom until the anchor is "hove short" and the pull upon the shank is almost directly upward. In order to increase the hold of the block 6 upon the bridge-piece, said block has upon each side tapering projections 15, with dovetailed or undercut edges adapted to corresponding recesses 16, formed in the bridge-piece 2, at 80 90 each side of the opening 3 therein.

In Fig. 5 I have illustrated a modification of my invention, in which a block 6^a instead of having a recess or socket for the reception of a projecting portion of the head of the shank has a projecting toe or lug 17, which is adapted to a recess or socket formed in the inner end of the head 10^a of the shank, so as to form a pivotal bearing upon which said head can swing. 95 100

Having thus described my invention, I claim and desire to secure by Letters Patent—

1. The combination in an anchor, of the flukes having a connecting bridge-piece with opening therein from the rear, said opening terminating at the forward end in a slot which is flanked by shoulders at the inner side, a shank having a head with opposite ribs for bearing against said shoulders, a block inserted into the opening of the bridge-piece from the rear and constituting a pivotal bearing for the inner end of the head of the shank, and means for securing said block in position, substantially as specified.
2. The combination in an anchor, of the flukes having a connecting bridge-piece, with opening therein terminating at the forward end in a slot, a shank passing through said slot, and having an enlarged head contained within the opening in the bridge-piece, and a block inserted in said opening from the rear and providing a pivotal bearing for said head of the shank, said block being so constructed that passages are formed between the same

and the bridge-piece of the shank, substantially as specified.

3. The combination in an anchor, of the flukes having a connecting bridge-piece with opening therein terminating at the forward end in a slot, a shank passing through said slot, and having an enlarged head contained in the opening of the bridge-piece, a block inserted in said opening from the rear and providing a pivotal bearing for the head of the shank, said block having at each side projecting lugs adapted to recesses in the bridge-piece at the opposite sides of the opening therein, and a retaining-bolt passing through the block and its lugs and through projecting rear portions of the bridge-piece, substantially as specified.

In testimony whereof I have signed my name to this specification in the presence of two subscribing witnesses.

PATRICK J. RYAN.
